COMBINATION HAT AND CLOTHES RACK

George W. Barlow, Aberdeen, Wash.

Application July 5, 1950, Serial No. 10,960

Term of patent 7 years

(Cl. D33—8)

To all whom it may concern:

Be it known that I, George W. Barlow, a citizen of the United States and a resident of Aberdeen, county of Grays Harbor, and State of Washington, have invented a new, original, and ornamental Design for a Combination Hat and Clothes Rack, of which the following is a specification, reference being had to the accompanying drawing, forming a part thereof.

In the drawing:

Fig. 1 is a perspective view of a combination hat and clothes rack, showing my new design; Fig. 2 is an end elevation of the same; and Fig. 3 is a top plan view.

I claim:

The ornamental design for a combination hat and clothes rack, substantially as shown.

GEORGE W. BARLOW.
